UNITED STATES PATENT OFFICE.

KARL ARNSTEIN, OF FRIEDRICHSHAFEN-ON-THE-BODENSEE, GERMANY, ASSIGNOR
TO THE FIRM: LUFTSCHIFFBAU ZEPPELIN GESELLSCHAFT MIT BESCHRÄNKTER
HAFTUNG, OF FRIEDRICHSHAFEN-ON-THE-BODENSEE, GERMANY.

AIRSHIP FRAME.

Application filed March 21, 1923, Serial No. 626,709, and in Germany September 7, 1922.

My invention has reference to novel means for stiffening the hulls of airships, and it refers particularly to the stiffening of the annular frames forming part of the hulls of 5 rigid airships.

In accordance with my invention provision is made to connect each of the corner points of these frames with all the other corner points thereof with the exception of 10 those directly adjacent the particular corner point from which the tightening wires extend; and in the practice of my invention I preferably proceed by connecting the corner points with all the other corners of the 15 frame with the exception of two neighboring corner points on either side of the particular points in question.

By this means a uniform and highly resistive tightening and stiffening of the different sections and of all the corner points 20 is produced. The resultant of forces at the corner points bisects the angle formed at each particular corner point. In the case of a lateral straining of the wires in the 25 frames caused by the gas pressure of the walls of the several cells all the corner points will with this new method of stiffening be uniformly strained and the frame is compressed substantially without deformation. 30

In view of the fact that, as shown in the preferred form of construction, I am enabled to dispense with four wires at each corner point, a great saving in wires is obtained 35 combined with a maximum efficiency. The connection with the directly adjacent corner point may be dispensed with in view of the mutual stiffening of the frame sections. The stiffening connection with the next succeeding point is dispensed with, in accordance 40 with my invention, in view of the fact that this connection would result in a very unfavorable distribution of stresses on the frame due to the rather very slight inclination relatively to the two intercepted frame 45 sections and, moreover, on account of the but slight deflection of which wires of such small length are susceptible thereby transmitting extraordinary compression stresses 50 on the two elements intermediate the connected corners.

In the case of larger sized ships some of the wires, for instance the radial wires,

should be duplicated on account of the large forces to be absorbed and because it is not 55 feasible to exceed a certain thickness of the wire in view of the necessity of not interfering with the making of the wire loop. By my invention provision is made in this connection for avoiding the excessive formation of knots otherwise produced by the superposition of the wires in the center point, and in accordance with my invention means are provided to have the diametrical wires extend from one main corner point 60 to the opposite corner in pairs, being deflected in the middle by a loosely inserted 65 guide-ring.

This guide-ring, which may for instance assume the shape of a thimble or the like 70 or may be formed like a sheave, produces automatically a compensation of the tensions within a wire couple whereby the otherwise preferable combination with the arrangement of duplicate wires becomes possible. 75

In the case of rigid airships in which the bottom portions of the annular frames are connected to each other by a rigid framing, the wires in accordance with this invention should be operatively connected to points of 80 juncture of the framing, instead of extending from the corners of the frame. It is recommendable to arrange the wires in such a manner that the diametrical wires which extend from the upper points of juncture of 85 the framing, are intersected before the disc-shaped guide.

My invention is more clearly set forth on the accompanying drawings, on which three modifications embodying the principles of 90 my invention are shown diagrammatically by way of example. In the drawings—

Figures 1, 2 and 3 are representations of an annular frame with tightening wires in accordance with this invention and seen 95 in the direction of the longitudinal axis of the ship;

Figure 1 showing the stiffening of a frame of comparatively simple construction as ordinarily employed for ships of small size 100 and seen at right angle to the plane of the frame, while

Figures 2 and 3 illustrate on about the same scale the application of the new mode of tightening to frames as used for ships of 105 larger size.

As appears from Figure 1, the frame may be composed of twelve separate elements *a*. From the corners of the frame constituting the bearings for the longitudinal supports *b* there extend seven stiffening wires *c* . . . *c*⁷ to all the other corners with the exception of the two next adjacent pairs of corners on each side.

In Figure 2 a frame construction is shown which is particularly adapted for use in connection with ships of larger size. Here special trusses *f* are serving as elements which have an obtuse angle in their outer lines at *e*, thereby increasing the number of circumferential corners; but only the main corners *d* are points of juncture for the frame's elements and therefore only these corners are braced by wires *c*. Eight wires *c*¹ . . . *c*⁸ extend from each of the main corner points *d*. Instead of but one diametrical wire two such wires *c*⁴ and *c*⁵ are employed which are guided over the disc *g* and are there deflected.

In Figure 3 a form of construction is shown in which the lower frame sections *a*¹, *a*², *a*³, *a*⁴, indicated in dotted lines, are replaced by a large continuous frame element *h*. Here, in addition to the wires that connect the various points of juncture as explained above there are wires *C*¹—*C*⁴ which connect the middle portion of the frame element *h* to various points of juncture distanced from the ends of frame element *h* by more than one juncture point. These wires are one half fastened at the point *i* and are half fastened at the point *k*, but if the portion of element *h* which includes points *i* and *k* be considered as a unit it will be seen that this portion is connected to various juncture points in the same way as would be the case if this portion of frame member *h* were itself a juncture point to the framing *h* at the points of juncture *i* and *k*. The diametrical wires *c*⁴ in this case are crossed before reaching the guide disc *g*.

While I have shown upon the accompanying diagrams the invention as applied to frames with an even number of sides, the invention is not restricted thereto, but may be employed also in connection with frames of an odd number of sides in which the wires or other cross stiffening members are only approximately diametrical. It is obvious, moreover, that the invention is capable of various other modifications and alterations to suit varying conditions of use and within the scope of the claims as hereunto appended.

I claim:

1. A rigid airship hull, comprising a longitudinal member and a cross member, said cross member constituting a substantially annular polygonal frame composed of individual elements, joining in points of juncture, each of said points of juncture being

connected by tension members to every other point of juncture within said frame distanced from the originating point by more than two of such points of juncture.

2. A rigid airship hull, comprising a longitudinal member and a cross member, said cross member constituting a substantially annular polygonal frame composed of individual elements joining in points of juncture, each of said points of juncture being connected by tension members to every other point of juncture within said frame distanced from the originating point by more than two of such points of juncture, said tension members being arranged in pairs where they connect points of juncture situated substantially diametrically opposite to each other.

3. A rigid airship hull, comprising a longitudinal member and a cross member, said cross member constituting a substantially annular polygonal frame composed of individual elements joining in points of juncture, each of said points of juncture being connected by tension members to every other point of juncture within said frame distanced from the originating point over more than two of such points of juncture, said tension members being arranged in pairs where they connect points of juncture situated substantially diametrically opposite to each other, and a central guide member between each of the two tension members constituting a pair of tension members.

4. A rigid airship hull, comprising a longitudinal member and a cross member, said cross member constituting a substantially annular polygonal frame composed of individual elements joining in points of juncture, each of said points of juncture being connected by tension members to every other point of juncture within said frame distanced from the originating point over more than two of such points of juncture, said tension members being arranged in pairs where they connect points of juncture situated substantially diametrically opposite to each other, and a guide-ring between each of the two tension members constituting a pair of tension members.

5. A rigid airship hull, comprising a longitudinal member and a cross member, said cross member constituting a substantially annular polygonal frame composed of individual elements joining in points of juncture, each of said points of juncture being connected by tension members to every point of juncture within said frame distanced from the originating point over more than two of such points of juncture, one of said elements extending over a larger sector of said polygonal frame than the other elements, a portion of said larger element intermediate its ends being likewise connected by tension members to all said points of

5 juncture distanced from the ends of said element by more than one juncture point, said tension members being arranged in pairs where they connect portions situated substantially diametrically opposite to each other.

6. A rigid airship hull, comprising a longitudinal member and a cross member, said cross member constituting a substantially 10 annular polygonal frame composed of individual elements joining in points of juncture, each of said points of juncture being connected by tension members to every other point of juncture within said frame distanced from the originating point over more than two of such points of juncture, one of 15 said elements extending over a larger sector of said polygonal frame than the other elements, a portion of said longer element intermediate its ends likewise connected by tension members to all said points of juncture distanced from the end of said element by 20 more than one juncture point, said tension members being arranged in pairs where they connect portions situated substantially diametrically opposite to each other, and a central guide member between each of the two 25 tension members constituting a pair of tension members, a portion of said longer element intermediate its ends likewise connected by tension members to all said points of juncture distanced from the end of said element by more than one juncture point, said tension members being arranged in pairs where they connect portions situated substantially diametrically opposite to each other, and a central guide member between each of the two tension members constituting a pair of tension members.

30 7. A rigid airship hull, comprising a lon-

gitudinal member and a cross member, said cross member constituting a substantially annular polygonal frame composed of individual elements joining in points of juncture, each of said points of juncture being 35 connected by tension members to every other point of juncture within said frame distanced from the originating point over more than two of such points of juncture, one of said elements extending over a larger sector 40 of said polygonal frame than the other elements, a portion of said longer element intermediate its ends likewise connected by tension members to all said points of juncture distanced from the end of said element by 45 more than one juncture point, said tension members being arranged in pairs where they connect portions situated substantially diametrically opposite to each other, and a central guide member between each of the two 50 tension members constituting a pair of tension members, the tension members constituting that pair which connects a portion of the said longer element with a point substantially diametrically opposite being arranged to intersect each other at a point between said guide member and said larger element. 55

In testimony whereof I affix my signature.
KARL ARNSTEIN.
